BUCKET ELEVATOR

Elmer C. Slater, Columbus, Ohio, assignor to
The Jeffrey Manufacturing Company, Colum-
bus, Ohio, a corporation of Ohio

Application December 10, 1931
Serial No. 580,202

7 Claims. (Cl. 198—207)

The present invention relates to elevators for lifting material from a boot to a point of discharge, and is here shown as applied to bucket elevators.

5 It will be understood that the present disclosure is illustrative, and in no sense restrictive, of the invention, as it may be applied to elevators other than the specific type shown, and its mechanical make-up can also be varied from that disclosed. 10 The invention has for its object to provide an elevator construction in which adjustment of the flexible conveyor for the purpose of taking up slack may be made without varying the working relation of that conveyor to the hopper which receives the material to be elevated, so that the same operative relation of the elevating instrumentalities to the mass to be lifted will be maintained. Furthermore, the construction is such that elevator chain slack may be taken up without the necessity of disassembling the elevator shaft or boot with which such elevators are ordinarily used, the adjustments being made readily from the outside of the shaft or boot.

15 The object of my invention is accomplished by 25 providing adjustable bearings in which a shaft, here shown as the foot shaft for the flexible elevating element, is mounted, so that, by adjusting the bearings, the flexible elevating element or chain may be adjusted for slack, and, further- 30 more, providing a hopper in which the buckets or equivalent elevating devices carried by the chain operate, supported by and adjustable with the bearings, so that the bearings and the material receiving hopper will take the same adjustments 35 and be held always in the same relation to one another.

In the drawing herewith is disclosed one physical embodiment of my invention, and in said drawing:—

40 Figure 1 is a side elevation of an elevator boot and a portion of an elevator stack, with my invention applied thereto.

Figure 2 is a sectional view substantially on the line 2—2 of Figure 1, looking in the direction of 45 the arrow, certain parts being shown in elevation for clearness of illustration.

Figure 3 is a view substantially on the line 3—3 of Figure 2, looking in the direction of the arrows, and

50 Figure 4 is a view substantially on the line 4—4 of Fig. 2, looking in the direction of the arrows.

Referring to the drawing by numbers, like numbers indicating like parts in the several views, 10 indicates the boot of the elevator structure, made up of angle irons and plates in ac-

cordance with any approved construction, said boot having any suitable receiving aperture 11 through which the material being handled may be poured. Rising from said boot is an elevator stack 12 of any suitable construction in which 60 travels the flexible elevator mechanism, here shown as a sprocket chain 13, provided with buckets 14, although it will be understood that other types of elevating devices may be used.

It is customary in equipment of this kind to 65 provide a foot shaft in the boot over which the chain will run, and a head shaft (not shown) at the top of the elevator stack over which the upper bight of the chain passes and at which point delivery of the elevated material is made, 70 the chain or other elevating element travelling in the direction of the arrows shown in Figure 1, so as to scoop the material from the boot on its down run and carry it upward to the delivery point on its up run.

75 It has been customary to use fixed hoppers in connection with devices of this kind, having curved bottoms conforming to the path of travel of the buckets, so that material delivered to the hoppers would be picked up and elevated. It 80 is not infrequently necessary to adjust the flexible elevating element or chain, which, through wear or stretching, develops slack, interfering with its efficiency, and some times causing a run-off of the chain from the pulley or sprocket 85 over which it travels.

In the present construction the bucket chain 13 is shown engaging a sprocket 15 mounted upon a shaft 16 which is carried in bearings 17, which bearings are adjustably hung from 90 screw shafts 18 pivotally coupled at 19 with said bearings, the screw shafts 18 being coupled with turning nuts 20 mounted in brackets 21 secured to angle irons 22 on the sides of the boot and provided with spanner holes by which they may 95 be turned in their seats in the brackets. The turning nuts have sprocket wheels 23 and are coupled across the boot by a chain 24 which extends transversely between the runs of the bucket elevator, so that it does not interfere with 100 the moving parts.

105 By this construction it will be seen that the bearings 17, the shaft 16, and the sprocket and bucket chain, can be raised and lowered simultaneously and evenly by turning a nut 20 on either side of the boot, so as to adjust the chain, to take out slack, or to ease the chain off, as may be desired.

110 The bearings 17 are provided with brackets 25, to which are secured a hopper 26, which, as shown

in Figure 1, is of an area to substantially fill the boot 10, it being here shown as of scoop formation, so that the material dumped into the mouth 11 of the boot will fall into the hopper 26. The 5 hopper may be fastened to the brackets 25 in any suitable way, as by means of bolts, so that upon adjustment of the shaft 16, bearings 17, and the bucket chain, the hopper 26 will also be adjusted and maintain always the same relation to the path of travel of the buckets 14. This 10 insures that the bucket load taken from the hopper 26 will not be effected by any relative movements of the hopper and the bucket. This has the advantage, of course, of maintaining a constant load for the bucket chain, and all danger, 15 such as existed in the old construction, where there was relative movement between the bucket chain and the hopper, of bringing the buckets too close to the bottom of the hopper in taking out slack, so as to interfere with the travel of the buckets, or of adjusting the buckets too far away 20 from the bottom of the hopper, in event of the chain being shortened, with consequent accumulation and packing of material in the bottom of the 25 hopper, is eliminated.

The sides of the boot are provided with lateral 30 openings 27 between the angle bars 22, so as to permit adjustments relative to the boot, and on each side of these openings, and preferably bolted 35 to the angle bars 22, as shown, are housings 28 to receive the bearings, the screw shafts 18 passing through apertures in the tops of the housings. In order that the bearings and their supported 40 parts may be properly held against side lash, and also guided in their up and down movements, the 45 housings 28 are provided with guide ribs 29 engaged by channel members 30 on the bearings, so that during the operation of the bucket chain, there can be no lateral shifting of the bearings, 50 and when the screw shafts are operated to raise and lower them, they will be accurately guided within the housings.

The hopper 26 is preferably guided, as shown 55 in Figures 2 and 3, by means of guide ribs 31 on the sides of the hopper which engage ribs 32 on the inner walls of the boot 10, these guiding 60 elements, as will be seen, being at right angles to the guiding elements for the bearings just described, so that, with this double set of guides, 65 any tendency of the hopper, the bearings, or the supported parts to shift or play during the operation of the machine is avoided, and, furthermore, the parts are accurately guided when adjustment is made.

It will be observed that the sides of the hopper 70 26 cover the apertures 27 in the walls of the boot from shaft downwardly, so that escape of dust is effectively prevented, and in order to guard against escape of dust at the upper end of the apertures 27, there is preferably provided shield 75 plates 33, which overlap corresponding shield plates 34, depending from the top of the hopper, as shown in Figure 2, so that objectionable escape of dust through the upper part of the aperture 27 is eliminated. Preferably, and as here shown, the depending shield plates 34 will be joined to the side walls of the boot by downwardly inclined sections 35, so that there are no abrupt projections against which the buckets on the chain can catch.

The hopper at its rear end, as shown in Figure 1, is provided with a shield plate 36 which overlaps and projects behind a complementary shield plate 37 secured to the rear wall of the 75 boot.

The boot may be provided, as shown in Figure 1, with any suitable hand hole in its wall, covered by a suitable cover plate 38, so as to permit inspection or the removal of foreign particles lodged in the hopper, without the necessity of taking it down.

From the foregoing, it will be seen that an elevator is provided which may be readily adapted to existing boots and stacks without involving any substantial changes in the general set-up and by means of which the active elements of the equipment, namely, the elevating chain and the material receiving hopper, can be maintained always in the same relative position, no matter what adjustments may be made. Furthermore, the adjustments may be readily made without the necessity of dismantling or taking down the boot or stack, so that, after once installed, the shifts necessary to take out slack or to ease off the chain may be quickly and conveniently made.

Such changes from the disclosure here made as are mere mechanical variations can, of course, be made and still remain within the purview of my invention.

I claim:

1. In elevating apparatus, a boot having vertically extending slots in opposite side walls thereof, outwardly projecting boxes secured to said boot in closing relation to said slots, shaft journals guided in said boxes for vertical adjustment, a conveyor foot shaft journaled in said journals, a hopper connected to said journals for adjustment therewith and means to vertically adjust and support said shaft and hopper with respect to the boot.

2. In elevating apparatus, a boot having vertically extending slots in opposite side walls thereof, outwardly projecting boxes secured to said boot in closing relation to said slots, shaft journals guided in said boxes for vertical adjustment, vertically extending suspension rods passed through apertures in the tops of said boxes and connected at their lower ends to said journals, means for supporting and vertically adjusting said suspension rods and therewith said journals, a conveyor foot shaft journaled in said journals, and a hopper connected to said journals for adjustment therewith.

3. In elevating apparatus, a boot having vertically extending slots in opposite side walls thereof, outwardly projecting boxes secured to said boot in closing relation to said slots, vertically extending parallel ribs in each of said boxes, bearing blocks engaging said ribs to be guided thereby for vertical adjustment, and a conveyor foot shaft journaled in said bearing blocks, said boxes including removable cover plates.

4. In elevating apparatus, a boot, a conveyor foot shaft extending across the boot, vertically adjustable bearing blocks supporting said foot shaft, vertically extending suspension rods pivoted at their lower ends to said bearing blocks on horizontal axes transverse to the shaft axis, and means for supporting and vertically adjusting said rods.

5. In elevating apparatus, a boot, a conveyor foot shaft extending across the boot, vertically adjustable bearings supporting said foot shaft, a hopper comprising a bottom portion and a top portion, said hopper being supported by said bearings intermediate the depth of the hopper, and band-like portions secured to the boot and depending therefrom and into the top portion of said hopper.

6. In elevating apparatus, a boot, a conveyor foot shaft extending across the boot, the boot having vertically extending guide-ways in its side wall, bearing blocks supporting the ends of said shaft and vertically movable in said guide-ways, vertically extending parallel ribs in said guide-ways engaging said bearing blocks to prevent axial movement thereof, a hopper supported on said bearing blocks for vertical movement there-
10 with, and vertically extending ribs on the boot engaging said hopper to prevent lateral move-
ment thereof with respect to said shaft.

7. In elevating apparatus, a boot, a conveyor foot shaft extending across the boot, vertically adjustable bearings supporting said foot shaft, a hopper supported by said bearings for adjust-
ment therewith, said hopper being secured to 80 the bearings at a point intermediate the depth of the hopper, the portion of the walls of the hopper above said bearings being outwardly flared, and means depending from the walls of said boot and into the outwardly flared portions 85 of said hopper.
